UNITED STATES PATENT OFFICE.

CALVIN ELI HAGERMAN, OF AINSWORTH, NEBRASKA.

HAY-RACK.

SPECIFICATION forming part of Letters Patent No. 380,106, dated March 27, 1888.

Application filed April 5, 1887. Serial No. 233,720. (No model.)

To all whom it may concern:

Be it known that I, CALVIN ELI HAGERMAN, of Ainsworth, in the county of Brown and State of Nebraska, have invented a new and 5 Improved Hay-Rack, of which the following is a full, clear, and exact description.

My invention relates to a hay-rack adapted to be carried upon a wagon, and has for its object to provide a rack of light weight, yet commodious, whereby hay or grain-straw may be carried from the field to the stack or market without danger of disarrangement, and also wherein the same may be loaded thereon and unloaded therefrom in windy weather with 15 comparatively little waste.

The invention consists in the construction and combination of the several parts, as will be hereinafter fully set forth, and pointed out in the claims.

20 Reference is to be had to the accompanying drawings, forming a part of this specification, in which similar letters of reference indicate corresponding parts in both figures.

Figure 1 is a vertical and transverse section 25 through the rack on line *x* of Fig. 2, and Fig. Fig. 2 is a plan view thereof.

In carrying out the invention a rectangular box-like base, A, is provided, designed to rest upon the wagon-bolsters in the ordinary manner, and having a series of horizontally-arranged apertures, *a*, in each side at the bottom, as shown in Fig. 1, the apertures upon one side being slightly out of alignment with the apertures upon the opposite side.

30 The end frame of the rack is constructed by attaching centrally and perpendicularly to each end of the body a slat or rail, D, of a length substantially equal to the desired height of the rack, the said rails being made to terminate at their upper ends in a knob, *d'*. At each side of the rail D', at the lower end and abutting against the same, another slat or rail D is secured to the body, adapted to extend in opposite directions upward and outward the 45 height of the central rail, as shown in Fig. 1, the end frame being completed by the attachment of a cross-bar, *d*, to the inner faces of the rails below the knobs *d'*, which cross-bars are made to project outward beyond the inclined 50 rails D.

The side portions, B' and B², of the rack are made detachable from the body and ends, and consist of a series of parallel beams, B, held a proper distance apart by one or more longitudinal strips, C, of any suitable light material, preferably wood, attached to the under side a distance from the outer ends of the beams; and the inner ends, *b*, of said beams are cut at an angle, (shown in Fig. 1,) to enter the body-apertures *a*.

60 The side portions, B' and B², alike in construction, are positioned upon the body by placing the inner strip, C, in substantial engagement with the upper edge of the side boards, and inserting the reduced inner ends 65 of the beams B into the various apertures *a* in the opposite side board, whereby the beams of each side portion, B' and B², cross in the body, as shown, and the said side portions are given an upward inclination. The now inclined 70 beams B are of such a length as that their upper and outer edges are practically in the same plane with the outer ends of the cross-bars *d*.

Gates H are provided each side portion, B' and B², of a length equal to the entire length 75 of the rack, constructed by attaching to a series of short beams, *h*, strips of board *h'*, or other equivalent light material, one end of said beams being left uncovered, are utilized as a means of hinging the gates to the afore- 80 said beams B. This is usually effected by passing a rod, H', through the lower ends of said short beams *h*, and also through the outer ends of the beams B, as shown.

The gates H are provided at each upper end 85 with a recess adapted to receive the ends of the cross-bars *d*, whereby the gates are closed flush with the same, and the gates are held in a closed position by means of hooks G, pivoted to the end of the rack, engaging a staple, 90 *g*, attached to the gate or other equivalent device.

It will be observed that in mounting the 95 rack upon the bolster of a wagon but little exertion is required, as the body and attached ends may be first placed in position, the bottom of which body may be made detachable and the side portions, including the gates, be then secured to the body.

The gates H, when the wagon carrying the 100

rack is not in use, may be opened and allowed to drop vertically downward, whereby the wheels and a greater portion of the wagon will be protected from the rays of the sun, and

5 when the wagon is returning from the field or meadow the gates may be folded in upon the beams B, and the sides thereby be left partially open.

In operation one gate is let down, as indicated by arrows in Fig. 1, and the hay thrown in from that side. When the rack is partially filled, the gate is closed and the remainder is thrown over the gate.

The gates are very advantageous in unloading, as when the vehicle is driven to the stack and the gate next thereto let down the hay, straw, or clover carried is readily and easily pitched off with little waste and slight exertion. In windy weather the weather-gate may be made to act in the capacity of a wind-brake. It will also be observed that in the form of rack described a load may be evenly placed without danger of displacement. Should the load be built high centrally, a rope may be stretched across to bear upon it, the said rope being fastened to the knobs d'.

Having thus described my invention, what I claim as new, and desire to secure by Letters Patent, is—

30 1. In a hay-rack, the combination, with the inclined side bars, B' B², and end bars D D' d, of the longitudinally-arranged hinged gates H, substantially as and for the purpose described.

35 2. The combination, with the box-body A, having apertures a, of detachable inclined side bars, B' B², engaging with said apertures,

and detachable end bars, D D' d, and longitudinally-arranged hinged gates H, hung to said side bars, substantially as and for the purpose described.

3. The combination, with the box-body A, having apertures a, of detachable inclined side bars, B' B², engaging with said apertures, and detachable inclined end bars, D D, perpendicular bar D', and horizontal stay-bar d, said side bars being provided with longitudinally-arranged hinged gates H, having means for locking them when closed, all substantially as and for the purposes described.

4. The combination, with the base-board having apertures a, of detachable inclined side bars, B' B², engaging with said apertures, detachable end bars, D D' d, and longitudinally-arranged hinged gates H, hung to said side bars, the gates being provided with eyes g, and the end portions with pivoted hooks G, adapted for engagement with said eyes, substantially as and for the purposes described.

5. The combination, with the base-board having apertures a, of detachable inclined side bars, B' B², engaging with said apertures, and detachable end bars, D D' d, said bars d being provided with angular pivoted hooks G, and said inclined side bars being provided with longitudinally-arranged hinged gates H, having eyes g on their outer sides, the said angular hooks G being adapted to engage said eyes, all substantially as shown and described, for the purposes described.

CALVIN ELI HAGERMANN.
